UNITED STATES PATENT OFFICE

ADOLPH L. DE LEEUW, OF PLAINFIELD, NEW JERSEY, ASSIGNOR OF ONE-HALF TO
ALBERT F. NATHAN, OF NEW YORK, N. Y.

MEANS AND METHOD OF DRESSING GRINDERS

Application filed December 18, 1927. Serial No. 239,704.

- This invention relates to an improved method and apparatus for dressing the working faces of grind wheels and other abrading elements to a predetermined form or contour by a generating process and is so contrived as to be especially suitable for dressing the wheel of the grinding machine disclosed in my Patent No. 1,666,737, dated April 17, 1928.
- 10 Other objects and advantages will be in part indicated in the following description and in part rendered apparent therefrom in connection with the annexed drawings.
- To enable others skilled in the art so fully 15 to apprehend the underlying features hereof that they may embody the same in the various ways contemplated by this invention, drawings, depicting a preferred typical construction have been annexed as a part of 20 this disclosure and, in such drawings, like characters of reference denote corresponding parts throughout all the views, of which:—
- Figure 1 is a fragmentary plan view of an improved gear grinding machine showing 25 the wheel truing device as it is used. Fig. 2 is an enlarged plan view, partly in section, of the wheel truing device showing the driving mechanism therefor. Fig. 3 is a vertical sectional view of a gear grinding machine 30 showing the means for advancing the abrasive wheel and truing device during the dressing operation. Fig. 4 is an enlarged portion of the abrasive wheel showing diagrammatically the path of one of the reciprocating diamond points. Fig. 5 is a plan view of the reciprocating diamond points and the method 35 of dressing the abrasive wheel so that a radial section thereof is in exact conformity with an accurately ground gear tooth. Fig. 6 is a representation of a modified form of wheel dressing device mounted on the base of the machine and the grinding wheel adapted to be moved into engagement therewith, as more fully described in my above indicated patent.
- 40 As shown in Figs. 1 and 3, the wheel dressing unit D is slidably mounted on a revolving table 10 which is made integral with a large stem 11. The stem 11 is translatable but not rotatably mounted in the sleeve 12 which is 45 driven by suitable worm gearing (not shown) located in the base of the machine. For a more complete and detailed description of the machine, reference may be had to my copending application filed March 23, 1926, Serial Number 96,706. Suffice it to say that the table 55 10 is rotated as well as translated; the purpose of which is to cause the grinding wheel, adjustably mounted on the table so as to move therewith, progressively to follow a helical path, the space between each two convolutions 60 being very small.
- Since the gear blanks, *a*, *b*, *c*, etc., are to be developed by a grinding operation, the blanks must roll with respect to the properly contoured periphery of the grinding 65 wheel. To this end the blanks are mounted on one end of a spindle 13, carried by an adjustable bracket 131. On the other end of the spindle is mounted a master pinion 14 in mesh with a master gear 15, having a relatively prime number of teeth. It is sufficient in this disclosure to assume there is but one grinding wheel and that it initially coincides with a given tooth of the prime gear. If *N* represents the number of teeth on the 70 prime gear 15, and *n* represents the number of teeth on the master pinion 14, then after the prime gear has rotated *n* times the original tooth of the prime gear will again be in contact with the original tooth of the master 75 pinion. Thus, it will be seen that since the grind wheel 16 is mounted directly over the prime gear and its contour in cross section is in exact conformity with a given tooth on the prime gear 15, *n* revolutions of the table 80 10 will cause the abrasive wheel to grind every tooth of the gear blank. As hereinbefore mentioned, the table, while rotating, is fed downwardly very slowly. Consequently 85 the path of the grinding wheel is in the form of a helix having closely spaced convolutions. Hence, if the operation is repeated, such convolutions in the aggregate will equal the width of the gear-blank.
- 90 As shown in Fig. 3, a stack of gear blanks 95 may be mounted on the spindle 13 and if there are a plurality of spindles; such for example, as shown in Fig. 1, there is constant gradual wear on the abrasive wheel. It has been found desirable, therefore, to at- 100

tach to the machine an automatic wheel truing device to maintain absolute accuracy in the grinding of any quantity of gears.

Since the abrading wheel must be initially formed and, from time to time, re-formed to compensate for its gradual wear, this invention provides means for automatically doing that in such a manner that the contour of the abrading section will correspond with the average contour of the teeth of the prime gear at all times.

Utilization is made of the principle that the involute form of the tooth approaches a straight line at its limit as the diameter of the pitch circle increases in size. When that diameter becomes infinite, its periphery becomes a rack, and the sides of the teeth of the rack become geometrically straight. Therefore, if a given pinion be replaced by a rack, the grinding wheel would likewise develop straight sided teeth in a rack-blank and, conversely, if the rack-blank be regarded as an abrader and if its teeth were formed with accurate straight sides, then it would dress the abrasive wheel into a tooth-contour conforming accurately to the master tooth of the prime gear 15. Inasmuch as an abrasive rack is impractical, it is proposed to employ two diamond points each representing one side of the hypothetical abrasive rack and continuously to reciprocate those diamond points rapidly in straight lines to simulate the straight sides of the hypothetical abrasive rack. Such points will serve to dress the grinding wheel accurately to its proper contour.

The actual construction may now be understood by referring to Figs. 1 and 2 in which 29 is a bracket, mounted on the plate 17 so as to permit oscillatory movement, and having secured thereto, at its lower edge, a plate 30; the front edge 31 of which represents the pitch line of the hypothetical rack before mentioned. Fixed to the plate 17 is a second plate 32, having a stepped marginal portion; the edges 33 and 34 of which are arcuately formed to represent a portion of the pitch circle and base circle, respectively, of the prime gear 15.

By holding the surface 31 of the rack plate 30 firmly against the surface 33 of the plate 32 (in such a manner that no tangential movement of the rack plate 30 takes place with respect to the arcuate plate 32) and giving the plate 30 a rolling movement, the resulting effect is the same as though the two members were a true rack and a gear.

This invention proposes a novel means for holding the plate 30 against the plate 32 without relying on frictional contact alone, or resorting to the costly operation of machining rack teeth and gear teeth on the two plates. This is accomplished in the manner now to be described.

One end of a flexible non-elastic strap 35

is securely fastened to the stepped plate 32 by means of a drive pin 36. The strap extends at a tangent to the base circle 34 along a line which ordinarily would be the normal pressure angle between a rack and gear of this size. The other end is fastened to a pin 37 projecting from the plate 30. A similar strap 38 has one end fastened to the plate 32, by means of the drive pin 39, and extends tangentially from the base circle 33 along a line corresponding to the pressure angle, and is fastened to a pin 40 projecting from the rack plate 30.

The principle involved here may be more readily understood by wrapping a cord around a small disc placed concentric with a slightly larger one. The periphery of the large disc will serve to represent the pitch circle of a gear wheel and the periphery of the smaller disc serving to represent the base circle. By holding the cord taut and at the same time unwrapping it from the disc, any point on the cord will trace a true and exact involute curve. If two cords are wound in opposite directions around the disc and have their outer ends fastened to the ends of a straight edge contacting with the periphery of the larger disc, it is at once apparent that as one cord is unwrapped the other winds up, and a given point on the straight edge will therefore trace an exact involute curve also. Since one cord cannot unwind any faster than the other cord winds up, the straight edge is held tightly against the pitch circle and is prevented from moving endwise. Thus, it will be seen that the plate 30 has no rectilinear movement relative to the plate 32 and the result is an accurate engagement of the two members, the straps 35 and 38 causing the plates to function in a manner identical with the action of a rack and gear connection.

As shown in Figs. 2 and 3, a rocking motion may be imparted to the plate 30 to cause it to roll about the periphery or pitch circle of the plate 32 without relative tangential movement, which is the converse of a gear rolling in a rack.

The diamond points 41 and 42 are securely held in slide rods 43 and 44 slidably mounted on the bracket 29 and in a plane containing the axis of the grinding wheel. The slide rods are inclined in conformity with the sides of a rack tooth and have rack teeth cut on the inner side of one end for engagement with the teeth of a wide faced pinion 45. The other extremities of these slide rods are offset and provided with diamond points so that these points are each located in the same horizontal plane containing the axis of the grinding wheel.

Means to reciprocate the slide rods rapidly and to oscillate the bracket is provided in this instance by a motor 46 mounted on a vertical axis. A helical gear 47, secured to the motor

shaft, meshes with a similar gear 47' on a shaft 48 journaled in a casing secured to the bracket 29. Integral with the shaft 48 are worm gears 49 and 50, the worm 49 driving a 5 worm-wheel 51 which carries the link 52 pivoted eccentric thereto. The other end of the link 52 is pivoted to a lever 53 connected to a shaft 54, the upper end of which has the wide faced pinion 45 mounted thereon. Thus, it 10 will be seen that rotary movement of the shaft 48 imparts an oscillatory movement to the pinion 45 and a resultant reciprocatory movement to the diamond points 41 and 42 in the direction of the sides of an imaginary 15 rack tooth.

Oscillatory movements are imparted to the diamond points by means of the gear trains 50, 55, 56, and 57; the gear 57 carrying one 20 end of the eccentrically pivoted link 58, the other end of which is pivoted to the plate 17. Rotary movement of the shaft 48 consequently 25 imparts an oscillatory movement to the bracket 29 relative to the plate 17. Bolts 29^a co-acting with slots 29^b serve to clamp the bracket 29 to the plate 17 to prevent any lifting or overturning movement thereof.

To insure that the diamond points do not retrace the same path, before the entire abrading surface of the grinding wheel has been 30 dressed to shape, the speed of the reciprocating gear train and the oscillatory gear train is such that the latter runs slower than the former to cause the result shown diagrammatically in Fig. 4.

35 Figs. 4 and 5 show diagrammatically the action of the diamond points on the abrading wheel; the figures being enlarged several times. As the slide-bar 44 moves in the direction of the arrow *d*, the slide bar 43 moves 40 in the opposite direction, and conversely, and since the abrading wheel is turning in the direction of the arrow *e*, the diamond point 42 on the slide rod follows a path indicated by the line *f*. The spaces between the lines 45 *f*, representing the paths of the diamond point, have been made unduly large to avoid confusion, but it is to be understood that in actual practice the spaces between the paths of the tool are very minute and over-lap as 50 indicated at *J*, Fig. 4. As hereinbefore stated, the reciprocation of the diamond points are in straight lines congruent with the sides of a rack, and since the bracket 29, carrying the slide rods 43 and 44, is given 55 an oscillatory movement to simulate the relative movements between a rack and gear, the diamond points consequently follow a path indicated by the arrows *g* and *k*. In this manner, the proper form is maintained on the

60 abrasive wheel at all times since the diamond points are kept in close contact with the periphery of the grinding wheel and continuously remove any projecting portions thereof.

65 Due to the wear on the abrasive wheel, caused by the grinding operation, the dia-

mond points must necessarily be advanced slightly in order to dress the wheel properly. This may be accomplished in various ways, one of which is shown in Fig. 3. On the under side of the bracket 29, a shaft 23 is 70 threaded through a nut 60 fixed to the bracket. The shaft is rotated by means of a worm-wheel 24 meshed with a worm 25 mounted on the upper end of the shaft 26. The lower end of the shaft 26 carries a six station wheel 27, which, as the table 10 rotates, is periodically engaged by a fixed stop 28 projecting from the base of the machine. 75

80 Means is provided for advancing the grinding wheel 16 to compensate for the infinitesimal amount removed by the action of the diamond points, which means consists of a nut 19 fixed to the under side of the plate 17 through which a shaft 20 is threaded. The outer end of the shaft carries a gear 21, 85 which is driven by a pinion 22 mounted on the shaft 23. As will be apparent from Figs. 2 and 3, the gears 22 and 23 are so ratioed that the bracket 29 is advanced substantially twice as fast as the slide 17 and thus the diamond points are kept in contact with the 90 grinding wheel during the continuous advance of the wheel toward the gear-blanks. Although only a single grinding attachment has been referred to as carried by the table 95 10, it is to be understood that, to increase production, the table may be equipped with a plurality of such attachments. Fig. 1 shows two grinding attachments carried by the table and with this arrangement each rotation of the table will effect two grinding operations: The grinding unit, shown in dotted lines, is a duplicate of the unit shown in full lines, hereinbefore described and detailed description thereof is deemed unnecessary. To 100 enable two grinding attachments to be secured upon the table, the attachments are preferably located at one side of the axis of the table, as shown in Fig. 1. With this arrangement, the dressing attachment D is positioned at an angle with respect to the center line of the abrading wheel (Figs. 1, 2 and 5) in order that the correct tooth angle be formed on the wheel to coincide with the underlying tooth of the prime gear 15. 105

110 The operation of the machine is as follows:—The operator loads the machine with a number of gear blanks, as shown in Figs. 1 and 3, sets the grind wheel in proper relation to the gear blanks and starts the machine. The grind wheel is rotated at a conventional speed and is carried in spiral path downwardly, during which it engages and grinds all the teeth on the gear blanks without further attention from the attendant. 115 During the grinding operation, the dressing attachment automatically maintains the grind wheel in proper form in the manner hereinbefore set forth.

120 From the foregoing, it will be perceived

that this invention provides a unique and accurate means for automatically maintaining a grinding wheel in a desired form. Obviously, the same result may be accomplished by various other arrangements utilizing the same principle. As shown in Fig. 6, the dressing attachment may be mounted on a bracket 75 secured to the base of the machine. A straight tooth rack 76 is slidably mounted in its lower end and a carriage 77 slidably mounted in its upper end; the slideways being accurately parallel with a straight line tangential to the pitch circle of the prime gear 15. The carriage 75 carries the diamond points and the mechanism for reciprocating them in a manner similar to the manner previously described. This tangential relation may accurately be secured by straight edge plate 78 fixed to the rack 76 and brought to bear peripherally against a ring 79 accurately formed to correspond to the pitch circle of the prime gear 15. The shaft 80 terminating in gears 81 and 82 (accurately meshing with appropriate racks) cause the carriage 75 to 25 counterpart all of the movements of the rack 76 or the carriage 75 and the rack 76 may be constituted as a single element slidably mounted on the bracket 75. With this arrangement, the grinding wheel is gradually 30 shifted horizontally towards the region of the reciprocating diamond points until it has completely attained the appropriate contour; the prime gear 15 being in a state of motion during its operation.

35 The result will be in either arrangement that the grinding wheel will be accurately conditioned and will be enabled, in its own turn, to grind accurate gears.

Without further analysis, the foregoing 40 will so fully reveal the gist of this invention that others can, by applying current knowledge, readily adapt it for various utilizations by retaining one or more of the features that, from the standpoint of the prior art, 45 fairly constitute essential characteristics of either the generic or specific aspects of this invention and, therefor, such adaptations should be, and are intended to be, comprehended within the meaning and range of 50 equivalency of the following claims.

Having thus revealed this invention, I 55 claim as new and desire to secure the following combinations and elements, or equivalents thereof, by Letters Patent of United States:—

1. The method of dressing the periphery of 60 an abrasive wheel into an adopted involute tooth-section, consisting in rotating said wheel about its own axis; causing a diamond point rapidly to reciprocate in a radial plane of the wheel and in a straight-line at an angle coincident with a side of an adopted rack-tooth; and simultaneously laterally rolling 65 the path of said diamond point about a center

lying on the base circle of said adopted tooth section while acting on said wheel.

2. A wheel dressing device combining a plate member having one edge shaped to correspond with the pitch circle of a given gear; a base member having one edge thereof engaging the edge of said plate member; means to hold said members in close contact; a grinding wheel mounted on one of said members; a diamond point reciprocably mounted on the other of said members and adapted to true said wheel; and means simultaneously to reciprocate said diamond and to cause relative rolling movement between the members. 75

3. A grinding machine comprising a grinding wheel and a dressing mechanism therefor; said mechanism comprising two slides angularly disposed and carrying diamonds at their extremities; and means for simultaneously oscillating and repeatedly reciprocating said slides to cause said diamonds to develop a predetermined contour on said grinding wheel. 85

4. A grinding machine combining a grind wheel; a rotatable support for said grind wheel; a wheel truing device mounted upon said support and adapted to dress said wheel; a work-support; means actuated by the movement of said rotatable support to feed said wheel toward said work-support; and means actuated in timed relation with the feed of said wheel to maintain said truing device in engagement therewith. 95

5. The method of dressing the periphery of 100 a grind wheel to the form of an annular gear tooth which consists of continuously engaging the grind wheel with a dressing element; reciprocating the dressing element in the plane of the tooth-section across a portion of 105 the grind wheel periphery; rotating said wheel to present new areas thereof to the dressing element and simultaneously effecting relative lateral rolling movements between the wheel and the dressing element to 110 cause said dressing element to develop a predetermined contour on the peripheral portion of the grind wheel. 115

6. The method of dressing an abrading element to the form of an adopted gear tooth 115 which consists of engaging the abrading element with a dressing element; rapidly reciprocating the dressing element radially of and in the general plane of the adopted gear tooth of the abrading element across a portion 120 thereof; moving one of said elements in a direction transverse to the plane of the tooth section formed on the abrading element to present new areas to the dressing element and simultaneously effecting a relative lateral movement between said elements 125 while in dressing relationship to develop a predetermined shape on said abrading element.

7. The method of dressing the periphery of 130

an abrasive wheel into an adopted involute tooth-section, consisting in rotating said wheel about its own axis and simultaneously swinging it bodily about a central transverse axis into engagement with a diamond point; rapidly reciprocating the diamond in a radial plane of the said wheel and in a straight line at an angle coincident with the side of an adopted rack tooth; and simultaneously effecting relative lateral rolling movements between the wheel and the diamond point to develop a predetermined contour on said wheel.

8. A grinding wheel dressing mechanism comprising a grinding wheel; two slides angularly disposed and carrying diamonds at their extremities, and means including two power actuated eccentrics for simultaneously oscillating and repeatedly reciprocating said slides to cause said diamonds to develop a predetermined contour on said wheel.

9. A machine of the class described combining a grind wheel, said grind wheel in section having the contour of a gear tooth; a dressing element movable radially of said wheel and in the plane of the tooth section; power means including an eccentrically mounted link member for causing a relative rolling movement between the grind wheel and said dressing element to develop the face of the gear tooth section of the grind wheel in a straight line; and power means including an eccentrically mounted link member for rapidly reciprocating said dressing element while in engagement with said wheel.

35 10. A machine of the class described combining a grind wheel having its periphery formed in accordance with an adopted tooth section; a reciprocably mounted dressing element adapted to engage the tooth surface of said grinding wheel, power means including an eccentric for causing a relative rolling movement between said dressing element in a plane containing the axis of said wheel to develop the face of the tooth portion of said wheel in a straight line; and means to reciprocate said dressing element in a direction parallel to the face of the tooth portion of said wheel, including an eccentric device driven from said power means and operatively connected with said dressing element.

11. A dressing device for truing a grind wheel combining a pair of diamond holders slidably mounted and angularly disposed with respect to each other, diamonds mounted in said holders and adapted to engage portions of the grind wheel; a movable supporting bracket for said holders; means for reciprocating said holders radially of said wheel; and means for imparting simultaneously an oscillatory movement to said bracket to cause said diamonds to develop a predetermined contour on said wheel.

12. The herein described method of dressing a portion of a grind wheel into an adopted tooth-section which consists in applying a

dressing element to the grind wheel, reciprocating the dressing element radially of said wheel and simultaneously laterally rolling the path of movement of the dressing element in the plane of the tooth-section while in dressing engagement therewith, and rotating the grind wheel to present unfinished areas to the dressing element.

13. A grinding machine comprising a grind wheel and a dressing mechanism therefor, said mechanism comprising two slides angularly disposed and carrying diamonds at their extremities; means for simultaneously oscillating and repeatedly reciprocating said slides to cause said diamonds to develop a predetermined contour on said wheel; power operated means for feeding the grind-wheel toward the work to be ground; and means actuated in timed relation with the feed of said wheel to maintain said dressing mechanism in engagement therewith.

14. A wheel dressing device combining a plate member having one edge shaped to correspond with the pitch circle of a given gear; a base member having one edge thereof engaging the edge of said plate member; flexible means for holding said members in close contact; a grinding wheel mounted on one of said members; a diamond point reciprocably mounted on the other of said members and adapted to true said wheel; and means including a prime mover adapted simultaneously to reciprocate said diamond and to cause relative rolling movement between the members.

15. A grinding machine comprising a grinding wheel and a dressing mechanism therefor; said mechanism comprising two slides angularly disposed and carrying diamonds at their extremities; a movable supporting bracket for said slides; and means for effecting simultaneously a combined oscillatory and reciprocatory motion to said slides to cause said diamonds to develop a predetermined contour on said grinding wheel.

In witness whereof, I hereunto subscribe my name.

ADOLPH L. DE LEEUW.
